UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

BALANCED SPLICE BAR FOR RUNNING RAILS.

Application filed July 5, 1927. Serial No. 203,511.

This invention relates to the subject of rail joints and more particularly to that class of rail joints which provide not only for the mechanical joining of the rail ends but also 5 permit the free "running" of the rail without impairment of the joint and without imposing shearing strains on the track spikes.

To that end the invention contemplates what may well be termed a splice bar for 10 "running" rail and also adapted for rail joint purposes at frog and switch locations in the track. Some railroad engineers prefer the use of rail joints which not only meet the usual standard requirements, but which 15 also have no spike slots or spike notches therein, thereby permitting the joint freely to run with the rail without interference from the spikes and without shearing strains on the latter. To meet all of these requirements is the problem met by the present invention, and the problem involves an unusual 20 distribution of metal in the bar to compensate for the reduction in the elastic limit of the bar which occurs when any truncation is 25 made in the foot flange or toe thereof in which the spike slots or notches are usually located.

Accordingly, the present invention provides a splice bar having no projecting part 30 beyond the outer edge of the rail flange, while at the same time having a deep and substantial spike head bearing surface, permitting spiking to the ties without restraining the rail joint from movement with the rail when 35 it "runs". At the same time the present invention involves a special distribution of metal in the lower half of the bar which is so related to the distribution of metal in the upper half of the bar as to substantially balance the upper and lower halves of the bar, particularly as to the static moment and as 40 to the $\frac{S}{A}$ ratios. Thus, the present invention provides a practical form of bar for free 45 running rail and at the same time improving the ratios of metal distribution in such a way as to counter-act and compensate for the weakness which would otherwise result from making a bar of this kind.

With these and other objects in view which

will readily appear to those familiar with the art the invention consists in the novel structural shape of splice bar with the improved metal ratios herein illustrated, described and claimed; and while the invention 55 is necessarily susceptible of structural modification without departing from the spirit and scope thereof, certain practical embodiments are shown in the drawings by way of example. In these drawings 60

Figure 1 is a sectional view of a complete rail joint for running rail, showing the improved balanced splice bars and the relation of the track spikes thereto.

Figure 2 is a half-view of a rail joint showing in full lines the improved splice bar superposed over a conventional form of splice bar having the usual spiking flange or toe and adapted for the same size and weight of rail; this conventional splice bar being 70 shown in dotted lines thereby to illustrate graphically the radical metal distribution required to bring about the new structural shape.

Figure 3 is a view similar to Fig. 1 showing the improvement incorporated in a bar adapted for a smaller size and weight of rail than that shown in Fig. 1, thereby illustrating the general range of equivalents falling within the present invention. 80

The invention may more readily be understood first by reference to the graphic illustration of Fig. 2 of the drawings illustrating, by dotted lines, the conventional form of splice bar S of the well-known 100% 85 reinforced type, which splice bar S is provided with the usual outstanding foot flange or toe f which for some railroads is required to be punched or slotted to provide spike openings through which the track spikes are 90 driven. This conventional angle form of splice bar is well designed and has a satisfactory metal distribution therein, but it is not adapted for free running rails where track spikes are desired at the joint locations. 95 That would be the fact even though the conventional splice bar S of Fig. 2 had its foot flange f sheared off on the shear line indicated by x to bring the flange within the outer edge of the rail base flange. Such al- 100

eration of the conventional splice bar S would greatly impair its metal distribution besides greatly reducing the elastic limit of the bar, rendering it undesirable for the 5 special purpose referred to.

Meeting the problem above described the present invention as shown in Fig. 2 of the drawings provides a structural shape for a splice bar including its substantially vertical web portion 1, an enlarged laterally widened head portion 2 and an enlarged laterally widened foot portion 3. The metal in the web 1 of the bar is so distributed and located as to be substantially bisected by the vertical plane of the outerside of the rail head, thus providing a form of splice bar in which the opposite bars of the joint have a much less out-to-out than the out-to-out of joint bars of the conventional type S indicated in 10 Fig. 2. In other words this construction materially lessens the distance between the outer vertical bolting face 4 of the bar web and the web of the rail and makes it possible to form the enlarged widened foot portion 3 15 of the improved splice bar with a spiking toe 5 overlying the upperside of the rail flange and having its outermost portion or edge 6 lying entirely inside of the outer edge of the rail base flange. At the same time this spiking toe 5 is formed at its upperside with a deep spike head engaging surface that conforms to and is adapted to be engaged by the underside of the head 8 of the usual track spike 9.

53 In connection with the spike toe formation 5 of the improved splice bar it will be observed that the said spiking toe is very materially thickened vertically in conjunction with the inner enlarged heel projection 40 10 of the foot portion 3. This heel projection 10 is specially formed in conjunction with the vertically thickened spiking toe 5 to bring about an improved metal ratio distribution. To that end the said heel 45 projection 10 is intended to extend inwardly substantially beyond the vertical plane of the inner edge of the lower fishing surface, that is to say its surface extends inwardly and upwardly, as indicated by the line 11 to a point 50 a where it joins the downwardly and inwardly sloping face 12 of the bar web to form an inner heel projection which is at least as great in vertical thickness as the spiking toe 5 as shown in Fig. 3 and preferably of greater vertical thickness than the vertical thickness of the spiking toe 5 as 55 shown in Fig. 1.

By reason of this special formation of the lower part or foot portion of the splice bar 60 the reduction in the elastic limit of the bar due to cutting off the outstanding foot flange thereof is counteracted and compensated for by substantially balancing the ratios of metal in the upper and lower halves of the bar 65 respectively above and below a middle line

or axis, which in the bar shown in Fig. 1 happens to be the horizontal neutral axis thereof. That is particularly true of the balancing of the static moments respectively in the upper and lower portions of the bar 70 above and below the said middle line or axis and also a substantial balancing of the $\frac{I}{S}$

and the $\frac{S}{A}$ ratios, which results in having 75 the center lines of stress and the centers of gravity of the said upper and lower portions of the bar respectively at substantially the same distances above and below the said middle line or axis. In further explanation 80 of this phase of the invention it is here noted that the static moment (S) of a particular area is the product of that area multiplied by the distance from an assumed axis of rotation to its neutral axis parallel 85 to the assumed axis of rotation. This physical property of a bar bears an important relation both to the moment of inertia (I) and to the area (A) in any distribution of metal in the bar. Accordingly, the present invention utilizes the desirable feature of 90 having the $\frac{S}{A}$ ratio of metal distribution in the upper unsymmetrical part of the bar 95 substantially equivalent to the $\frac{S}{A}$ metal distribution in the lower unsymmetrical part of the bar. This results in locating the center line of gravity for the upper part of the bar substantially at the same distance from the horizontal axis or middle line of the bar as the center line of gravity for the lower part of the bar is disposed below said axis or middle line. In other words, the centers 100 of gravity may be properly disposed by a proper static area ratio obtained by dividing the static moment (S) of the section by its area (A). The inertia static $(\frac{I}{S})$ obtained 110 by dividing the moment of inertia of the section by its static moment relates to a ratio of metal distribution which provides for properly disposing the center lines of stress in the bar respectively above and below its 115 neutral axis or middle.

From the foregoing it is thought that the structural features and special advantages of the improved splice bar will be understood by those familiar with the subject without further description and it will of course be understood that changes in the form, proportion and minor details of construction may be resorted to without departing from the spirit or sacrificing any of the advantages 120 of the invention.

I claim:—

1. A balanced unsymmetrical splice bar provided with an enlarged laterally widened foot portion provided with a thickened spik- 130

ing toe adapted to lie entirely within the outer edge of the rail flange, the said widened foot portion having a proportional distribution of metal therein, with relation to the metal distribution of the upper unsymmetrical portion of the bar thereby to provide a substantial equivalence between the $\frac{S}{A}$ ratios of metal distribution for the upper and lower unsymmetrical portions of the bar.

2. An unsymmetrical splice bar section provided with an enlarged laterally widened foot portion having a thickened spiking toe adapted to lie entirely within the outer edge of the rail base flange and with an inner enlarged heel projection having a vertical

thickness at least equal to the vertical thickness of the said spiking toe.

3. A balanced unsymmetrical splice bar for "running" rails having a substantial equivalence between the static moments of the upper and lower unsymmetrical portions thereof and provided with an enlarged laterally widened foot portion provided with a vertical thickened spiking toe adapted to lie entirely inside of the outer edge of the rail base flange and with an inner enlarged heel projection having a vertical thickness of at least the same as the vertical thickness of the said spiking toe.

In testimony whereof I hereunto affix my signature.

VICTOR C. ARMSTRONG.
